UNITED STATES PATENT OFFICE

CHARLEY W. BERGANDER, OF CHICAGO, ILLINOIS, ASSIGNOR TO BRITESUN, INCORPORATED, OF CHICAGO, ILLINOIS, A CORPORATION OF ILLINOIS

ELECTRIC ARC LAMP

Application filed September 29, 1927. Serial No. 222,833.

My invention relates to electric arc lamps and has for its object the provision of means whereby the arc between the carbons or electrodes of such a lamp may be quickly established by manipulation.

In carrying out the invention, one of the carbons or electrodes of such a lamp is provided with means whereby it may be placed by hand into contact with the complementary 10 carbon or electrode and may be separated from such carbon, following the establishment of the circuit through the lamp, to a limited extent which is determined by a stop.

The lamp of my invention, in its preferred 15 embodiment, is of the Jablockoff type in which the carbons are placed abreast and converge to the location of the arc, the carbons being in contact when the circuit of the lamp is initially established and being drawn 20 apart to establish the arc. In the preferred embodiment of my invention, the carbons or electrodes are maintained at a given angle during their consumption, the arcing ends 25 of the carbons being brought into arc establishing relation by the straight line movement of one carbon holder transversely to the other, that is, transversely to the axes of the carbons.

The invention will be more fully explained 30 by reference to the accompanying drawings in which Fig. 1 is an end view of an electric arc lamp as it is constructed in accordance with the preferred embodiment of my invention; Fig. 2 is a longitudinal sectional view 35 of the lamp, the carbon pencils being broken away and the reflector that is usually employed being removed; Fig. 3 is a side view of a portion of the lamp structure taken on line 3—3 of Fig. 2; Fig. 4 is a sectional view 40 on line 4—4 of Fig. 2; and Fig. 5 is another longitudinal sectional view of the lamp structure with the reflector shown in place, a portion 45 of the reflector being broken away.

The electric arc lamp illustrated is a therapeutic lamp adapted to emit violet rays, though the invention is not to be limited to the purpose of the lamp. It is housed within a hood 1 which is suitably supported. A mounting plate 2 is formed with ears 3 and 50 is secured within the hood by means of screws

4, said plate being perpendicular to the axis of the lamp and having an oblong slot 5 whose geometrical center is on the axis of the lamp. A metallic carbon holder 6 passes through the slot 5 and has a base portion 7 which is 55 fixedly secured to a plate 2, at the rear side of the plate, by means of screws 8, the holder being insulated from said plate, the plate being desirably metallic. Another metallic carbon holder 9 also passes through the slot 60 5 and has a base portion 10 upon the rear side of the mounting plate. This base portion 10 is secured to the arm 11 by means of screws 12, this arm being pivoted to and upon the rear side of said mounting plate by means 65 of the pivot bolt or screw 13. The arm 11, being preferably metallic, is insulated from the carbon holder 9.

The carbon holders are included in the lamp circuit to convey current to and from the carbons or electrodes 14 and 15 that are secured 70 therein by clamping screws 16 and 17. The axes of the carbon receiving elements 6 and 9 converge forwardly so that the carbons, which are held abreast, also converge forwardly. The carbons are brought together at their unmounted ends for initially establishing a lamp circuit. When the lamp circuit has been established the arc is established by drawing the carbon 15 away from 80 the carbon 14. The adjustment of the carbon 15 is effected by suitable swinging movement of the arm 11.

A threaded rod 18 is screwed into and 85 passes through an enlargement 19 that is formed upon the arm 11. This rod passes to the exterior of the hood 1 and through the key hole slot 20 formed in this hood. A nut 21 is screwed upon the rod. This nut 90 may be adjustable upon the rod or may be fixed thereto. It, in effect, constitutes a shoulder upon the rod. In assembling the rod with the aforesaid arm, the rod is inserted through the larger end of the key hole slot until the shoulder 21 also is passed through 95 the larger end of the key hole slot whereafter the rod is shifted along toward the narrower end of this slot and is screwed into the arm enlargement 19, a knob 18' being desirably provided at the outer end of the rod. When the 100

rod has been assembled with the arm 11, it serves as a means, accessible from the exterior of the lamp, whereby the lamp may be swung in one direction to bring the carbon 15 in contact with the carbon 14 to establish the lamp circuit, and in a reverse direction to draw the arc. The carbon 14 serves as a stop to limit the movement of the arm 11 in a lamp circuit establishing direction. The movement of said arm in an arc drawing direction is limited by marginal portions of the slot 5 which serves as an abutment to engage the shoulder 21. When the rod 18 is pulled upon to establish the arc, it is usually moved until the shoulder 21 engages the hood 1 though it is obvious that the rod may be moved outwardly to a partial extent corresponding to the size of the arc desired. The size of the arc is determined by the extent to which the rod 18 is screwed into the arm enlargement 19. After the rod 18 has been suitably adjusted, it is only manipulated by pushing and pulling upon it except when it is desired to change the size of the arc.

25 The lamp of my invention is simple in operation and adjustment as will be apparent from the foregoing. The circuit is quickly established and the arc is quickly drawn due to the freedom of adjustment afforded for 30 the movably mounted carbon 15.

The term "carbon" or "carbons" is used herein in the sense of any electrodes between which arcs may be established.

Changes may be made without departing 35 from the invention.

Having thus described my invention, I claim:

1. In an electric arc lamp, the combination with two electrode holders, one of these 40 holders being normally shiftable in position and having a range of movement permitting the electrode therein to engage the electrode in the other holder and to be separated therefrom; a rod assembled with the shiftable 45 holder and having a shoulder thereon; and a stop with which said shoulder may be engaged to limit the extent to which the shiftable holder may be spaced apart from the other holder, said rod having threaded connection 50 where it is assembled with the shiftable holder to adjust the location of said shoulder, with respect to said stop.

2. In an electric arc lamp, the combination with two electrode holders, one of these 55 holders being normally swingingly mounted in position and having a range of movement permitting the electrode therein to engage the electrode in the other holder and to be separated therefrom; a rod assembled with 60 the swingingly mounted holder and having a shoulder thereon; and a stop with which said shoulder may be engaged to limit the extent to which the swingingly mounted holder may be spaced apart from the other holder, said 65 rod having threaded connection where it is

assembled with the swingingly mounted holder to adjust the location of said shoulder, with respect to said stop.

In witness whereof, I hereunto subscribe my name.

CHARLEY W. BERGANDER.
